US0D1107118S

(12) United States Design Patent (10) Patent No.: US D1,107,118 S
van Driel (45) Date of Patent: * Dec. 23, 2025

- (54) TABLETOP COIN PUSHER GAME
(71) Applicant: CVD Holding B.V., Zeist (NL)
(72) Inventor: Casper Clemens Antoon van Driel,
Amersfoort (NL)
(73) Assignee: CVD HOLDING B.V., Zeist (NL)
(*) Notice: Patent file contains an affidavit/declaration
under 37 CFR 1.130(b).
() Term: 15 Years
(21) Appl. No.: 35/521,823
(22) Filed: Aug. 1, 2023
(80) Hague Agreement Data

- Int. Filing Date: Aug. 1, 2023
Int. Reg. No.: DM/231329
Int. Reg. Date: Aug. 1, 2023
Int. Reg. Pub. Date: Aug. 2, 2024
(51) LOC (15) Cl. 21-01
(52) U.S. Cl.
USPC D21/325; D21/369
(58) Field of Classification Search
USPC D21/310, 324, 325, 329
CPC A63F 9/30; G07F 17/3297; G07F 17/32
See application file for complete search history.

(57) CLAIM

The ornamental design for a tabletop coin pusher game, as shown and described.

DESCRIPTION

1.1 : Front Perspective

1.2 : Front

1.3 : Back

1.4 : Left

1.5 : Right

1.6 : Top

1.7 : Bottom

1.8 : Perspective

The broken lines in the drawings depict portions of the tabletop coin pusher game that form no part of the claim. The broken line table, in reproduction 1.8, illustrates environmental structure and form no part of the claimed design.

1 Claim, 8 Drawing Sheets
